Primary Examiner — David Muller*Assistant Examiner* — Nathan Johnston(74) *Attorney, Agent, or Firm* — Servilla Whitney LLC(57) **CLAIM**

The ornamental designs for a syringe tip with indicator, substantially as shown and described.

DESCRIPTION

FIG. 1 is a perspective view of a syringe tip with indicator showing our new design in an environment in which it may be used;

FIG. 2 is a side elevation view thereof;

FIG. 3 is a side elevation view thereof;

FIG. 4 is a top plan view thereof; and,

FIG. 5 is a bottom plan view thereof.

Portions shown in broken lines represent unclaimed portions of the claimed design.
